UNITED STATES PATENT OFFICE.

HELEN DOHERTY AND JOSEPHINE LE BLAUC, OF PROVIDENCE, RHODE ISLAND.

GARMENT-PATTERN-DESIGNING SCROLL AND SQUARE.

Application filed December 28, 1923. Serial No. 683,229.

To all whom it may concern:

Be it known that we, HELEN DOHERTY and JOSEPHINE LE BLAUC, citizens of the United States of America, and residents of Providence, in the county of Providence and State of Rhode Island, have invented certain new and useful Improvements in Garment-Pattern-Designing Scrolls and Squares, of which the following is a specification.

This invention relates to means for laying off or drafting garment patterns or charts such as are usually delineated on paper from measurements taken from an individual.

The object of the invention is to provide a pattern delineating scroll or curve and a complementary square, by the use of which patterns may be accurately produced from individual measurements.

The object of the invention is also to provide a garment drafting scroll, the perimeter or marginal curves thereof being evolved from lines of the human figure, particularly of those parts of the body including the neck, shoulders, junction of the arms with the trunk, the bust and hip curves, the several lines of the scroll being assembled in proper relation to provide a laying off curvilinear or translating rule for use in delineating a pattern from and in accord with measurements taken from an individual.

A further object of the invention is to provide a garment pattern scroll which is made up of four main marginal curves with measure thereon which together provide six laying off curves, specifically a shoulder section, a combined hip and bust section, an armhole section, a neck section and a sleeve section, the combined sections of the scroll having three angles or corners, and a re-entering angle or recess, the sections between the angles being graduated and indicated on one side by numbers, the opposite side of the scroll being graduated and indicated by letters in duplicate located adjacent to alternate lines or graduations.

A further object of the invention is to provide a garment maker's scroll of such character and outline that patterns may be laid off or delineated therefrom to accord with measurements taken from individuals

with the usual tape measure, and in delineating the pattern or one half thereof, the scroll is used in conjunction with a square used to draw on the pattern lines or marks which are hereinafter designated as "building lines". The scroll or curve is nominated as a "J-curve" and is a combination of certain curves for use in producing patterns for garments, irrespective of the size and figure of the individual and in accord with measurements taken with a tape measure.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates one side of the curve; 75

Figure 2 illustrates the reverse side of the curve;

Figure 3 illustrates one side of the tailor square;

Figure 4 illustrates the reverse side of the tailor square; 80

Fig. 5 illustrates a pattern for a two piece waist; and

Fig. 6 illustrates a pattern of a two piece sleeve. 85

In these drawings, Figure 1 shows one side of the pattern curve which measures diagonal from A to B, 18½ inches, this length being made purposely to have each extending to the proper length for the largest draft as well as for the smallest draft. The side of the scroll or curve shown by Fig. 1 is marked with symbols of the alphabet from AA to ZZ, each symbol of double letters being 2 inches apart, the double letters being used to distinguish the curves of the scroll from the building lines which are marked by single letters.

The long edge or margin of the scroll from A to B is a composition of a slight concave curve and a large convex curve for laying off on the pattern, the hip and bust measurements, the ends of the curves adjoining the shoulder and the armhole sections of the

- scroll. The part of the scroll from A to C is intended for the hip curve, from C to B for the bust curve, these two curves being also used in participation for very pronounced hip and bust curves, one of the double letters of said curves being used in laying off the pattern. The part of the scroll from A to D represents the curve which adjoins the sleeve and hip curves and is for use for the shoulder line of the pattern of any size; D to E a compound curve adjoining shoulder and armhole curves which is used for sleeves, the same adjoining curve from E to F being used for back neck of pattern; E to B adjoining convex curve is used for front armhole of pattern, and adjoining neck and bust curve is used from E to G for front of neck of the pattern.
- Figure 2 shows the reverse side of the scroll and on this side all adjoining curves are numbered for two purposes, one to measure the curves made on the pattern and the other to distinguish clearly from the reverse scroll which has its gage lines alternately indicated by double letters AA to ZZ. In Figure 2, each adjoining curve has an indicating name marked thereunder to save time in locating said curves, in English and French. The scroll on its side that is lettered and spaced starts at the angle B, the lettering continuing to the angle A, and from thence to D, from D to the entering angle E, and from E to B, joining B at an acute angle. On this side of the scroll double lettering is used for convenience in laying off a pattern, as single letters are used thereon to indicate pattern lines and numbers for "building lines."
- The sections of the scroll are laid off as to measurements substantially as follows: From A² to B² includes hip and bust measures totaling 24 inches; from E² to B², 11 inches, armhole measure; from E² to D², 10 inches, for neck and sleeve measurements, and from D² to A² 7 inches for shoulder measurements. The length of the several margins of the scroll totals 52 inches. The spacing on the opposite side of the scroll is in inches and the indicating marks are in inches, and the lettering is applied to align with each alternate mark, the entire alphabet of twenty-six letters being used. Each number begins at each adjoining curve to facilitate measuring curves, A² to B² compound and adjoining curve, measures 24 inches; A² to C² in use for hip curves of the pattern; C² to B² in use for the bust curve of the pattern; A² to D² in use for the shoulder of the pattern and measures 7 inches; D² to E² compound curve in use for the sleeve of the pattern, measuring 10 inches, and the said curve is also used from E² to F² for the back neck of the pattern.

Each adjoining curve on the same side is

also marked with the metric system, thus enabling one to teach both a French and an American method, each adjoining curve being marked the same way with centimetres.

A² to B², the longer curve of the scroll, measures 61 centimetres (hip and bust). A² to C², or hip curve, measures 28 centimetres and 5 millimetres. A² to D², shoulder curve, measures 18 centimetres. D² to E², sleeve curve, measures 10 centimetres and 3 millimetres. E² to B², armhole, measures 28 centimetres and 5 millimetres. E² to F², used for the back of neck, measures 10 centimetres and 2 millimetres. E² to G², used for front of neck, measures 18 centimetres. At the adjoining of the neck and armhole curves, 1 centimetre is divided into 10 millimetres to show the division of centimetres and it is not repeated to avoid confusion with the inches.

The tailor square has a long and a short arm, the long arm being 21 inches and the short arm being 9 inches. One side (Fig. 3), has its long arm divided by lines into half inches, the inches being marked, the short arm of said side having the inches divided into quarters, and marked.

The reverse side (Fig. 4) has its long arm divided into scales of thirds and sixths, the former being on the outer edge of said side and the latter being above the former. Each scale is marked as shown. The short arm of the reverse side is divided into scales of eighths and fourths, the former being marked on the outer edge of the short arm and the latter being marked above the former, each scale with its indicating name being marked with an arrow, and the inches being marked on the inner edge of said short arm.

To make the building lines of the pattern when the metric system is employed, an ordinary metre is used wherein centimetres and millimetres instead of scales form the basis of calculation. Centimetres and millimetres, if marked on the tailor square will comprise the scales of the inches and make it almost impossible to distinguish the difference.

To lay off or draft a plain two piece waist pattern, as shown by Fig. 5, a piece of paper of appropriate size to draft thereon one-half of the waist pattern is laid upon a table; by using square, line 1, the length of back seam plus one-half an inch is drawn, the half-inch added being provided for hems. The corner of the square is next placed 5 inches from the top of paper after drafting line 1, and while in such position, the point A is located. The corner of the square is next placed at the bottom of line 1, with its long arm resting on the width of the paper, and line 2 is drawn. The square is now turned so that its short arm will be on line 2; next

measure up from line 2 along the long arm of square the under arm length 9 and indicate by point. The corner of the square is placed at this point with its short arm resting on top of line 1, and the bust line, which is one half of the bust measure, plus $1\frac{1}{2}$ inches, for turning under, is drawn and point B is placed at end of line; on this bust line 3, a few points as B, C, D are located 5 and made. From the corner of the square while on line 3, there is measured upward one half of the width of the back, plus $\frac{1}{4}$ of an inch, at which point C is placed. The neck line 4 is next made. From D the under arm point locate C and put corner of square with short arm resting on line 3 and make line 5, and with the corner of square at top of line 5 measure down one-eighth of armhole measure, and place E at the 10 terminal of measurement.

For the next plotting, the square is placed at top of line 1, the long arm resting on line 4, laying off one-sixth of neck and marking F at point. To form the neck curve, TT on scroll is placed at F and when that portion of scroll touches A, the curved line is made. For the shoulder curve, the corner of the scroll is placed at F and E drawn, the line being extended $\frac{1}{4}$ of an inch to provide for 25 folding.

The square may be next placed with its corner on the line 3 with its long arm on line 1, and a measure is made and marked, the corner of the square being moved thereto 30 so that its long arm will be at the end of back shoulder and draw line 6 which gives front shoulder line, a point G being indicated on draft, and on this line 6 is located H, the end of front shoulder line from H to 40 G being the length of the shoulder seam, to curve the shoulder line the scroll from A² to D² is used.

The corner of the square is next placed the same distance above H, as there is between the back shoulder line E, F to line 5, and front line 7 is drawn to point I. For neck, square is placed at point 7 and measure 45 is made, J being put at termination. The square is now placed below the point J, and line 8 is made, said line being one half of chest measure, plus $\frac{1}{4}$ of an inch, more or less, for turning under. To produce curve of neck, place the scroll so curve will touch points J and H.

To produce the rear curve of arm hole, the arm hole curve of scroll is placed to touch line 5 and point E, end of shoulder line, the balance of the arm hole portion of the scroll touches line 8, the chest line and ends at point G.

For the waist line, the square is put on point D with short arm on bust line 3 and vertical line 9 is drawn, the points K and L are located and converging dart lines are drawn therefrom to D. The scroll is used 60

between these points to give curvature to lines L—D and K—D, and finally the hip portion of the scroll is used to make the curve I to L.

What are known as the building lines are 70 numbered and are laid off from the square with scales used to locate the points, and the pattern lines are lettered to indicate that they are made from the margins of the scroll.

In drafting a pattern of a two piece sleeve, 75 a rectangular piece of paper 27 by 15 inches is used; the square is placed on the top of paper, and at a distance equal to one-third of the length of the sleeve, point A is placed and line 1, the under arm line is drawn.

Midway between upper edge of paper and 80 parallel with line 1 is located line 2, and point B being placed at half the arm hole measurement, plus $\frac{1}{2}$ an inch, and midway on this line, the point C is located, and from C is drawn line 3, the top of sleeve line.

The corner of the square is now placed at B and line 4 is made, which line is the length of sleeve from top to elbow, plus 1 inch, and at end of line 4, line 5 is made, said line extending to bottom edge of the paper. With the short arm of the square on line 5, locate and place point D, and measure upward one-half the wrist measure, plus 1 inch and mark 90 E. Now place the square at point D and E and make a line two-thirds of the wrist measure and indicated by F; also place G one-half an inch above D, and H at one-third the wrist measure above G. On line 4 measure

from B the length of sleeve from top to elbow and draw line 6, the elbow line, then measure up on line 6, $1\frac{1}{2}$ inches from the edge of the paper, and place I. From point I, measure on line 6 the distance from A to C and place J, which is connected by a diagonal line with point C, also connect point I with A, and I with G. Points H and J are connected by the scroll, placing the corner at junction of hip and shoulder curves, and line from J to H is drawn, the scroll is now moved with its point at F to junction of lines 4 and 6.

For the top of the sleeve curve, the corner D of the scroll is placed at outer end of line 3, to join point B, and to make back curve the corner D of scroll is placed at 3 and joins point A, and to make front curve the entering angle E is placed at point A and extends to point C.

In making this pattern it is requisite that the under piece of the sleeve be traced on another piece of paper, to produce a duplicate, the tracing or copy having lines from points A to C; C to J; J to H; H to D; D to I and from I to A.

We claim:

1. A one-piece or unit scroll for laying off dress patterns, the scroll having a margin bounded by different curves, each curve being separated from an adjacent curve by an 130

gles, one of said angles being a reentering angle, such reentering angle being located opposite the longest side of the scroll.

2. A scroll made up of a reversible unit comprising four differently curved sections for use in laying off from previously taken measures of a person the shoulder, hip, bust, armhole and neck outlines of a garment evolved from the scroll, said scroll having

three corners and a reentering angle between ¹⁰ which are four graduated sections of different curvatures, said scroll having its opposite faces graduated and marked by duplicate characters, the successive graduations on one face being in register with alternate ¹⁵ graduations on the other face.

HELEN DOHERTY.
JOSEPHINE LE BLAUC.
